UNITED STATES PATENT OFFICE.

JOHN H. COLLINS, OF LOS ANGELES, CALIFORNIA; LOTTIE PAYNE COLLINS, ADMINISTRATRIX OF SAID JOHN H. COLLINS, DECEASED.

PUMP.

Application filed July 21, 1921. Serial No. 486,345.

To all whom it may concern:

Be it known that I, JOHN H. COLLINS, a citizen of the United States, residing at Los Angeles, in the county of Los Angeles and State of California, have invented new and useful Improvements in Pumps, of which the following is a specification.

My invention relates to pumps of the type generally utilized for drawing relatively small quantities of liquid from a storage tank; the principal objects of my invention being to generally improve upon and simplify the construction of existing types of similar pumps, to provide a pump that is of relatively simple structure thereby permitting it to be manufactured at relatively low cost, and further to provide simple and efficient means for catching and retaining all drip or overflow from the pump spout or the container into which the liquid is discharged, and for returning said drip and overflow to the storage tank.

Further objects of my invention are to provide simple and efficient means for locking the pump while not in use, thereby preventing the unauthorized use of the pump, and further to provide a pump of the character described with means for preventing foreign substances, such as sand, dust, and water from entering the return tube and passing into the storage tank.

With the foregoing and other objects in view, my invention consists in certain novel features of construction and arrangement of parts that will be hereinafter more fully described and claimed and illustrated in the accompanying drawings, in which:

Fig. 1 is an elevational view of the pump with parts thereof in section.

Fig. 2 is a vertical section taken approximately on the line 2—2 of Fig. 1.

Fig. 3 is a horizontal section taken approximately on the line 3—3 of Fig. 1.

Referring by numerals to the accompanying drawings which illustrate a practical embodiment of my invention, 10 designates the cylindrical body of the pump, the same being preferably formed from a section of metal tubing of proper size, and arranged on the ends of said cylindrical body is an upper head 11 and the lower head 12, the same being connected and maintained in assembled relation by suitably located tie rods 13.

Secured in any suitable manner to the lower head 12 and depending therefrom is a

short tubular housing 14 from which projects laterally a tubular neck 15 that terminates in a horizontally disposed pan 16. This pan is of disc-like form and is provided with an upstanding marginal flange 17. Removably arranged within the pan 16 is a section 18 of reticulated material, such as wire netting, the same serving as a support for the containers that receive liquid discharged from the pump spout. Hinged to pan 16 and preferably at a point adjacent to tubular member 14 is a cover plate 19 for the pan 16, and arranged on the under side of said cover plate adjacent to its edge is a gasket or packing member 20 that is adapted to rest directly on top of flange 17 and provide a practically air and dust proof joint when the cover plate is closed.

The cover plate 19 is retained in closed position upon pan 16 by a suitable latching device 21 that is preferably located diametrically opposite the hinged point of said cover plate. The lower end of tubular member 14 is directly connected to the upper end of a tube 22 that extends downwardly and thence laterally to the lower end of a liquid storage tank (not shown).

Formed integral with or fixed to the lower portion of head 12 and positioned in the upper portion of tubular member 14 is a cage 25 to which is connected the upper end of the pump tube 26 that extends downward through the vertical leg of tube 22, and arranged in the upper portion of said cage 25 is a valve seat 27 upon which normally rests 28 an upwardly opening inlet check valve 28 preferably of the disc type.

Arranged for reciprocatory movement within the cylindrical body 10 of the pump is a piston 29 carrying on its periphery a cup packing member 30, and said piston being provided with one or more openings 31 that are normally closed by an upwardly opening check valve 32 preferably of the disc type. Connected in any suitable manner to the upper end of the piston 29 is the lower end of a pump rod 33 that is arranged for reciprocation through a gland or stuffing box 34 on the top of head 11. Pivotedly connected to the upper end of pump rod 33 is one end of a pump operating lever 35 that is provided on its lower or outer end with a handle 36, and there being a ring 37 formed on the lower end of said handle. Pivotedly connected to a bracket that projects outwardly

from lower head 12, is the lower end of a link 38, the upper end of which is connected to the intermediate portion of lever 35 by a relatively short link 38'. Pivotally mounted on the lower portion of link 38 is the inner end of a loop 39 that is adapted to receive the ring 37 on the lower end of lever 35 when the latter occupies a substantially vertical position, as illustrated in Fig. 3. When ring 37 is thus engaged through loop 39, the operating parts of the pump may be effectively locked by the application of the hasp of a suitable padlock 40 through the ring 37. Screw seated in the upper head 11 is the inner end of a tubular spout 41, the outer end of which is bent downwardly so that it occupies a position a suitable distance above the center of pan 16.

The operation of my improved pump is as follows:

Lid or cover plate 19 is swung upward so as to uncover pan 16, and the container that is to receive the liquid discharged from spout 41 is placed on the reticulated member 18. Handle 36 is now manually engaged and lever 35 is manipulated so as to reciprocate piston 31 within the pump cylinder, which action draws liquid from the storage tank upwardly through tube 26, and which liquid after passing through the alternately opening check valves 28 and 31 passes through the upper portion of the pump cylinder and discharges through spout 41 into the receptacle positioned on pan 16. Any overflow from this receptacle and likewise any drip from the spout 41 will pass from pan 16 into tubular member 15, and from thence said drip or overflow liquid will pass back to the storage tank through pipe 22.

After the receptacle has been removed from the pan 16, cover plate 19 is swung downwardly on to the top of said pan thereby effectively preventing foreign matter, such as dust, water and the like from entering the return tube 22 that leads to the storage tank. The depth and general form of the pan 16 is such as to prevent relatively thin liquids from splashing outwardly over the edges of the pan, and likewise for preventing relatively heavy liquids from piling up and overflowing as a result of their slow movements. Further, the capacity of the return tube 22 is much greater than the capacity of tube 26 that carries the liquid to the pump, and which arrangement prevents the drip pan from overflowing in the event that the flow of liquid from the pump is directed from the nozzle into the drip pan. Such construction insures the quick return of all characters of liquid to the point of storage.

By the use of the hand lever engaging de-

vice 39 and a suitable padlock, the operating parts of the pump may be effectively locked against use by unauthorized persons and consequently affording the desired protection where the pump is located on the outside of a building.

While my improved pump may be advantageously employed wherever relatively small quantities of liquid are periodically withdrawn from a storage tank, it is particularly adapted for use for the handling of fuel, lubricating and illuminating oils, and its use in connection therewith affords a relatively high degree of safety, economy, cleanliness and efficiency.

It will be understood that minor changes in size, form and construction of the various parts of my improved pump may be made and substituted for those herein shown and described without departing from the spirit of my invention, the scope of which is set forth in the appended claims.

I claim as my invention:

1. A pump comprising a body, a piston movable in the body and including a rod extending from the body, a lever pivotally connected to the outer end of the piston rod, a rod pivotally connected to the body, a link pivotally connecting the second rod with said lever, an eye formed on the free end of the lever, and a keeper pivoted on the second rod and adapted to pass over said eye so that when a lock engages the eye, the keeper will be locked to the lever.

2. A pump comprising a body, a piston movable in the body and including a rod extending from the body, a lever pivotally connected to the piston rod, a rod pivotally connected to the body, a link pivotally connecting the second rod with said lever, an eye formed on the free end of the lever, and means associated with the eye for locking the lever against movement.

3. A pump comprising a body, a piston movable in the body and including a rod extending from the body, a lever pivotally connected to the piston rod, a rod pivotally connected to the body, a link pivotally connecting the second rod with said lever, an eye formed on the free end of the lever, and co-acting means on the lever and second rod for locking the lever against movement.

4. A pump comprising a body, a piston movable in the body including a rod extending from the body, a lever pivotally connected to the piston rod, a second lever pivotally associated with the body, a link pivotally connecting the two levers, and means for locking both of the levers against movement.

In testimony whereof I have signed my name to this specification.

JOHN H. COLLINS.
